UNITED STATES PATENT OFFICE.

CHARLES D. FRENCH, OF EAST ANGUS, QUEBEC, CANADA.

FIGURE WHEELED TOY.

Application filed October 22, 1921. Serial No. 509,698.

To all whom it may concern:

Be it known that I, CHARLES D. FRENCH, a subject of the King of Great Britain, residing at East Angus, Province of Quebec, 5 Canada, have invented certain new and useful Improvements in Figure Wheeled Toys; and I do hereby declare that the following is a full, clear, and exact description of the invention, such as will enable others skilled 10 in the art to which it appertains to make and use the same.

The present invention relates to new and useful improvements in toys.

The primary object of the invention is 15 the provision of a wheeled toy combined with what is commonly known as a jumping jack, so that the latter will operate upon the wheeling motion of the said toy.

Another object of the invention is the 20 provision of a sounding means to be used in connection with a wheeled toy for operation when the same is moved over the ground.

A still further object of the invention is 25 the provision of a toy such as above referred to, which will be comparatively simple and inexpensive to manufacture, reliable and efficient in use, and readily operated.

With the above and other objects in view, 30 the present invention resides in the novel features of construction, formations, combinations and arrangements of parts to be hereinafter more fully described, claimed and illustrated in the accompanying drawings forming a part of the present application, and in which:

Figure 1 is a side view of one form of toy showing the same in one position;

Figure 2 is a plan view thereof;

Figure 3 is a view similar to Figure 1, 40 showing the mechanism in its opposite position;

Figure 4 is a view similar to Figure 1 with parts broken away showing a whistle employed in connection with the same;

Figure 5 is an enlarged sectional view 45 through a portion of the device disclosed in Figure 4; and

Figure 6 is a detail sectional view illustrating a quick release means for the jack.

Referring now to the accompanying drawings by corresponding characters of reference throughout the several views, and particularly to Figures 1 and 2 thereof, the numeral 1 designates in general a toy which 50 comprises an operating lever 2, the latter

having a handle 3 formed at one end thereof and a wheel 5 journaled at its opposite end.

A supporting plate is attached to the intermediate portion of the lever 2 and is indicated by the reference character 6, while pivoted to the upper portion thereof is a link 7 which is in turn pivotally connected to a link 8 which is connected at its opposite end eccentrically to the wheel 5. A rocker bar 9 is pivoted intermediate its ends to the lower end of the plate 6 and one end thereof is connected by a link 10 to the intermediate portion of the link 7, while the opposite end thereof is connected to a pitman 11 60 which is slidably mounted in a sleeve 12. This pitman 11 has secured to the upper end thereof a suitable object such as the head of a jumping jack shown at 13 which is slidably mounted in the sleeve so that upon the rotation of the wheel 5 the same will be raised and lowered alternately appearing and disappearing through the opening provided in the upper end of the sleeve.

Referring now to Figures 4 and 5, a modified form of the invention is provided in which a whistle 14 is seated in one of the openings 15 provided in the partition 16 which forms a guide for the pitman 11. A plate 17 is slidably mounted below the partition 16 and is provided with an opening 18 therein which alternately registers with the openings 15, thus permitting the whistle to blow, or preventing it from blowing, as 70 might be desired.

The plate 17 is normally held by a spring 19 so that the whistle 14 will be in inoperative position, but this plate 17 is connected by a rod 20 to a hand operating lever 21 so that the plate may be moved to such a position as 75 to permit the whistle to operate when desired.

The modified form shown in Figure 6 refers to a means for causing the quick appearing and disappearing of the head 13 and to this end instead of connecting the rocker bar 9 directly to the end of the pitman 11, a spring 22 is interposed therebetween and is connected to a link 23 which in turn is pivotally connected to the lower end of the pitman 11 one side of which is notched as at 24 to receive the curved end of a spring 25. Obviously this spring holds the head 13 in either its raised or lowered position until a suitable pressure is exerted thereon through the tension of the spring 22 which causes the spring 25 to disengage from the notches 24, 80 85 90 95 100 105 110

thus causing a quick movement of the head 13 in opposite directions.

From the foregoing description taken in connection with the accompanying drawings, it will be manifest that a toy is provided which will fulfil all of the necessary requirements of such a device, and it should be understood in this connection that various minor changes in the specific details of construction can be resorted to within the scope of the appended claims without departing from the spirit or sacrificing any of the advantages of the invention.

Having thus fully described the invention, what I claim as new and desire to protect by Letters Patent is:

1. The herein described toy comprising a lever, a wheel journaled thereon, a sleeve carried by the lever, a piston within said

sleeve, a head mounted upon the piston, a whistle operated by the piston, and means for throwing the whistle into or out of operation.

2. The herein described toy comprising a lever, a wheel mounted thereon, a sleeve having a piston therein, a partition disposed in the sleeve and formed with an opening, a whistle mounted in the opening, a plate having an opening therein adapted to register with the first named opening, means for operating said plate to open and close the opening in the partition, and an operative connection between the piston and wheel for actuating the piston.

In witness whereof I have hereunto set my hand.

CHARLES D. FRENCH.
